UNITED STATES PATENT OFFICE.

LUDWIG VON ORTH, OF BERLIN, GERMANY.

WIRE-HOLDER FOR TROLLEY-WIRES OF ELECTRIC RAILWAYS.

SPECIFICATION forming part of Letters Patent No. 721,734, dated March 3, 1903.

Application filed December 26, 1901. Serial No. 87,157. (No model.)

To all whom it may concern:

Be it known that I, LUDWIG VON ORTH, doctor of philosophy, a citizen of the German Empire, residing at 9 Ludwigskirchstrasse, Berlin W., Germany, have invented a new and useful Improvement in Wire-Holders for Trolley-Wires of Electric Railways, of which the following is a specification.

My invention relates to wire-holders for trolley-wires of electric railways; and it consists in fitting to the ordinary wire-holder wire-holding devices which are connected in a yielding manner with the wire-holder and secure the wire at points which are located on the farther side of the points of attachment on ordinary wire-holders.

The invention is shown in the accompanying drawings.

Figure 1 is a side elevation of an ordinary wire-holder with the end of a wire held thereby. Fig. 2 is a side elevation of a wire-holder according to my invention. Fig. 3 is a modification of the wire-holder shown in Fig. 2.

The part marked *a* is a non-flexible wire-holder of the ordinary kind, such as that shown alone in Fig. 1.

b is a flexible metal piece which is connected to the holder *a* and is provided with claws *c'*, *c²*, and *c³*.

d is the conducting-wire, which is held by the holder *a* and also by the claws *c'*, *c²*, and *c³*.

On the drawings there is only one metal piece *b* provided on one side of the holder; but, as a rule, I shall use such a metal piece with claws also on the other side of the holder, so that the conducting-wire *d* will be gripped on both sides of the holder *a* by claws *c*. The claws *c'*, *c²*, and *c³* are not rigidly connected to the holder *a*, but can slide in relation thereto for a purpose to be hereinafter described.

The modification shown in Fig. 3 of the new wire-holder differs from the arrangement according to Fig. 2 only in that the lateral flexible parts *b* are not connected directly to the middle part *a*, but are secured to separate insulators *e*.

The apparatus acts as follows: The metal piece *b*, with the claws *c'*, *c²*, and *c³*, certainly takes part in the oscillations of the wire *d*,

but offers a certain resistance thereto, so that the oscillations are diminished. The result is that the wire breaks less frequently than when it is held by the ordinary holder *a*; but in cases in which the wire breaks it is held by the claws *c'*, *c²*, and *c³*, as the breakage is always close to the holder *a*, as has been shown by experience.

In contradistinction to known arrangements for preventing damage when the wires break, by cutting off the current from the broken wires, in which case it must be assumed that an adjacent wire is present that is connected to the other pole, by my construction of wire-holder only the falling of broken wires is prevented without having to rely on the coöperation of another wire in order to cut off current from the broken wire. The new wire-holder can be used instead of ordinary known wire-holders without necessitating any alterations in the suspension of the conducting-wires.

My new wire-holder can be modified in various ways without departing from the spirit of the invention. Instead of providing the lateral holders *b* with three claws I may use any desired number of claws. The connection of the lateral holders *b* with the middle holder can be effected in any desired manner. Furthermore, I may arrange on each side of the middle holder two or more lateral holders *b*, since the only essential part of the invention is that in addition to the holder *a* at least one auxiliary holding device is used for the wire, which device can take part in the oscillations of the wire. This is necessary in order that the fracture of the wire may take place always between the point of attachment to the holder *a* and that of the auxiliary holding device.

Having now particularly described and ascertained the nature of my invention and in what manner the same is performed, I declare that what I claim is—

1. In a holder for electric-railway trolley-wires, the combination of a non-flexible holder adapted to support the strained wire, and an auxiliary flexible holder connected at one end to the non-flexible holder and at its other end

to the wire and being normally under no strain from said wire, substantially as and for the purpose set forth.

2. In a holder for electric-railway trolley-wires, the combination of a non-flexible holder adapted to support the strained wire, and an auxiliary flexible holder connected at one end to the non-flexible holder and provided at its other end with claws connected to the wire,

10 said flexible holder being normally under no strain from said wire, substantially as and for the purpose set forth.

Signed this 11th day of December, 1901, at Berlin.

LUDWIG VON ORTH.
